(57) **CLAIM**

The ornamental design for a fishhook ring accessory, as shown and described.

DESCRIPTION

FIG. 1 is a perspective view of the fishhook ring accessory;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

The broken lines shown in the Figures represent portions of the fishhook ring accessory that form no part of the claimed design.
